UNITED STATES PATENT OFFICE.

EZRA DEDERICK, OF MILWAUKEE, WISCONSIN.

DESIGN FOR A HOOK.

SPECIFICATION forming part of Design No. 31,578, dated October 3, 1899.

Application filed September 11, 1899. Serial No. 730,178. Term of patent 14 years.

To all whom it may concern:

Be it known that I, EZRA DEDERICK, of Milwaukee, in the county of Milwaukee and State of Wisconsin, have invented a new and original Design for Hooks, of which the following is a description, reference being had to the accompanying drawings, which are a part of this specification.

Figure 1 is a front edge view of a hook, showing my new design. Fig. 2 is a side view of the same hook. Fig. 3 is a sectional view on line 3 3 of Fig. 1.

As shown in the drawings, the leading or material feature of my design consists of a main or body part A and a terminal or loop part B, the body part having at the side the appearance of an elongated ring or link with straight parallel sides and rounded ends and the terminal looped part having at the same side view the appearance of an extension centrally from the end of the body part, the said loop part terminating, as appears in this side

view, in a spreading portion having a concave outer wall, the body part at a front edge view showing the front line or bar of the body to be divided and separated at an oblique angle to its length, the diminishing terminal portions of this line or bar of the body being opposite each other and being correspondingly twisted or turned from each other, and the terminal loop part at the same front view extending laterally from the body part and curving at its ends to a straight transverse terminal bar.

This hook may be of any size desired. 35

What I claim as my invention is—

The design for a hook, as herein shown and described.

In testimony whereof I affix my signature in presence of two witnesses.

EZRA DEDERICK.
